Design U.S. Appl. No. 29/468,841, filed Oct. 3, 2013 (pending).

Primary Examiner — Deanna L Pratt*Assistant Examiner* — Katie Mroczka(74) *Attorney, Agent, or Firm* — Nixon & Vanderhye PC(57) **CLAIM**

The ornamental design for a screen protection sheet, as shown.

DESCRIPTION

FIG. 1 is a front view of a screen protection sheet showing our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front view showing a front removable film thereof;

FIG. 8 is a front view showing a protection sheet thereof;

FIG. 9 is a front view showing a back removable film thereof;

FIG. 10 is an additional front view showing a cross-sectional position thereof; and,

FIG. 11 is an enlarged cross-sectional view taken along line 11-11 of FIG. 10 thereof.
